UNITED STATES PATENT OFFICE.

DANIEL M. RESSLAR AND FRANK BUTLER, OF MOUNT VERNON, OHIO.

CAPPING-TOOL.

1,077,301.

Specification of Letters Patent.

Patented Nov. 4, 1913.

Application filed February 8, 1913. Serial No. 747,126.

To all whom it may concern:

Be it known that we, DANIEL M. RESSLAR and FRANK BUTLER, citizens of the United States, residing at Mount Vernon, in the 5 county of Knox and State of Ohio, have invented certain new and useful Improvements in Capping-Tools, of which the following is a specification, reference being had to the accompanying drawings.

10 This invention relates to an improved capping tool of that character commonly employed for heating and severing glass cylinders, the invention having for its primary object to provide improved means 15 for taking up the expansion of the heating wire or tensioning the same.

Another object of the invention is to produce a device for the above purpose which may be conveniently operated by one hand, 20 and includes a body having the circuit wires arranged thereon and connected to the terminals to which the cylinder encircling wire is in turn connected, a trigger actuated member mounted upon said body 25 to engage the wire and tension the same, and a switch also mounted upon the body and located in the circuit, whereby said circuit may be opened or closed at the convenience of the operator.

30 Still another object of the invention is to produce a capping tool for the above purpose which is simple and inexpensive in its construction and very durable as well as efficient in operation.

35 With the above and other objects in view as will become apparent as the description proceeds, the invention consists in certain constructions, combinations and arrangements of the parts that I shall hereinafter 40 fully describe and claim.

For a full understanding of the invention, reference is to be had to the following description and accompanying drawing, in which—

45 Figure 1 is a side elevation of a cylinder capping tool embodying the present invention; Fig. 2 is a top plan view of the device; and Fig. 3 is a section taken on the line 3—3 of Fig. 1.

50 Referring in detail to the drawings, 5 designates the body of the device which is constructed of a suitable insulating material and includes an elongated arm 6 and an angularly disposed offset end 7, such offset 55 end serving as a hand grasp whereby the device may be conveniently manipulated.

Upon this offset end portion of the body or base, a suitable switch is mounted, said switch embodying the spaced contact members 8 to which the positive and negative 60 wires 9 from a suitable source of current supply are connected. These wires are extended upon one side of the body 5 and suitably secured thereto, the extremities of the wires being connected to the spaced 65 terminal members 10 and 11 mounted upon the extremity of the arm 6. The electric circuit is adapted to be closed by the movable switch member 12 which is suitably mounted in the switch casing and is normally held in its open position by means of a spring 13. The stem 14 of this movable member extends transversely of the hand 70 grasp 7 and in convenient position to be actuated by the thumb of the operator. 75

The terminal member 10 is in the form of a short plate fixed in the upper edge of the body 5, and this plate is provided with a slot 15 opening upon the upper edge and one end thereof. The other of the terminal members 11 is in the form of a bolt extending transversely through the arm 6 and upon one end of this bolt a sheave or roller 16 is loosely mounted. One end of a heating wire 17 is adapted to be connected to 80 the terminal bolt 11 and passed therefrom around the glass cylinder to be cut or severed. The wire is then returned and extended around the terminal sheave 16 and has its extremity passed through the slot 90 15 in the terminal plate 10. The wire is then suitably bent so as to retain the same in said slot. When the electric circuit is closed and the current passed through the wire 17, the same will of course expand and in order 95 to take up this expansion, and hold the wire in close engagement with the periphery of the glass cylinder, I provide a lever 18 which is of angular form and is fulcrumed at the juncture of its arms upon a stud 19 100 fixed in the base or body 5. One of these arms extends above the upper edge of the arm 6 of the body and is provided with a short longitudinal slot or recess 20 which is adapted to receive the wire 17 at a point 105 adjacent to the end thereof which is disposed through the opening 15 of the terminal plate. To the other arm of this lever which extends inwardly upon the base or body member 5, one end of a link 21 is pivotally connected. The other end of this link 110 is pivoted to a trigger member 22 which is

5 pivotally mounted at one of its ends in an elongated recess 23 formed in the lower edge of the arm 6 of the body, upon the stud 24 secured to said body. This trigger member 10 at its pivoted end is provided with a downwardly and forwardly curved extension 25 positioned in close proximity to the hand grasp 7 for engagement by the forefinger of the operator. A spring 26 is connected 15 at its ends to the body and to said trigger member respectively and normally acts to hold said trigger member against pivotal movement and within the recess 23 of the arm 6. A stop pin 27 is secured to 20 the arm 6 and with the same, the inner end of the lever 18 is adapted to engage to limit its movement in one direction.

From the foregoing, the operation of the device will be readily understood. After 25 the heating wire has been passed around the glass cylinder and around the terminal sheave 16, the same is then disposed in the slot in the outer end of the lever 18 and connected to the terminal plate 10 in the manner above described. The operator then 30 closes the electric circuit by actuating the movable switch member so that the wire 17 becomes highly heated, and finally cuts its way through the wall of the glass cylinder. 35 When the wire expands as it is heated by the electric current, such expansion is taken up by means of the lever 18 which is actuated by the operator pulling upon the thumb piece of the trigger 22 with his forefinger, thereby throwing the outer end of the lever 40 18 upwardly and inwardly to exert a pull upon the wire, thus maintaining the same in close engagement with the periphery of the glass cylinder. By providing this improved 45 tensioning means for the heating wire, the necessity of pulling the same by hand to tension the wire as it expands, is obviated. The operator is often subjected to a severe shock and the wire often is engaged with 50 one of the protruding metal parts of the capping bar or stick, thus causing a short circuit. It will be obvious that by means of the present invention, these several objections are obviated and a device produced 55 which will at all times hold the heated wire in engagement with the glass cylinder and which may be easily and quickly actuated with one hand by the operator.

It will, of course, be obvious that in carrying out our invention, we do not wish to 55 be limited to the specific form of switch illustrated in the accompanying drawing; as many different forms of switches now upon the market may be employed. The terminals 10 and 11 can also be so arranged with 60 relation to each other so that the glass cylinder can be cut at any desired angle. The invention is also susceptible of many other modifications in the form, proportions and arrangement of the several parts without 65 departing from the essential features thereof or sacrificing any of its advantages.

Having thus described the invention, what is claimed is:

1. A device of the character described including a body provided with a hand grasp and having suitable conductors and terminals, a heating wire connected with such terminals and adapted to be passed around the article to be severed, a circuit closer 75 for the conductors positioned adjacent the hand grasp, and manually operated means positioned adjacent the hand grasp for tensioning said wire. 70

2. A device of the character described including a body provided with a hand grasp and having conductors and terminals, a heating wire engaged with said terminals and adapted to encircle the article to be severed, and manually operable tensioning means for 85 the wire positioned adjacent to the hand grasp. 80

3. A device of the character described including a body affording a hand grasp and having suitable terminals and conductors, a circuit closer for the conductors carried by the hand grasp provided with a reciprocating stem directed transversely of the hand grasp, a heating wire operatively engaged with the terminals, and manually operable tensioning means for the wire positioned adjacent the hand grasp. 90 95

In testimony whereof we hereunto affix our signatures in the presence of two witnesses.

DANIEL M. RESSLAR,
FRANK BUTLER.
